UNITED STATES PATENT OFFICE.

FREDRIK LJUNGSTRÖM, OF STOCKHOLM, SWEDEN, ASSIGNOR TO AKTIEBOLAGET LJUNGSTRÖMS ÅNGTURBIN, OF LILJEHOLMEN, SWEDEN.

STEAM-TURBINE.

1,074,370.

Specification of Letters Patent. Patented Sept. 30, 1913.

Application filed February 4, 1913. Serial No. 746,168.

To all whom it may concern:

Be it known that I, FREDRIK LJUNGSTRÖM, a subject of the King of Sweden, residing at 2 Drottningholmsvägen, Stockholm, in 5 the Kingdom of Sweden, have invented certain new and useful Improvements in Steam-Turbines, of which the following is a specification.

In steam turbines, especially radial turbines with wheels rotating in opposite directions, the steam is led into hollow chambers which are arranged laterally of the rotary wheels and which surround the shafts. Hitherto it has been usual to admit the 10 steam through tubes which open laterally in the said chambers. As, however, the steam, when so admitted, causes unequal heating of the chambers at the heating of the turbine, for instance at the starting, especially when 15 superheated steam is employed, because those parts of the chambers which are situated nearest to the inlet place obtain the highest temperature, the disadvantage arises that the chambers are set obliquely, whereby the 20 spaces in the labyrinth and shaft-tightenings supported by said chambers are increased by the wear of the tightening rings in such a manner that they will be greater than is 25 suited to proper working.

30 The present invention has for its object to avoid the said disadvantage. This is attained by distributing the steam in the chambers by means of special distributing organs, whereby a uniform heating of the 35 chamber is obtained.

Some embodiments of the invention are shown in the accompanying drawings.

Figure 1 shows one of these partly in side elevation and partly in longitudinal section. 40 Fig. 2 is a cross-section on the line A—B of Fig. 1. Figs. 3, 4 and 5 show three other embodiments in cross-section.

In the embodiment shown in Figs. 1 and 2, *a* indicates the turbine casing, *b* the steam admitting tubes and *c* the chambers to which the steam is admitted and which are placed laterally of the turbine wheels (not shown), which are concentrically arranged between the chambers. Said chambers support as usual the labyrinth- and shaft-packing *n*, which are separate parts secured to the said chambers, having an annular space or interval between them. Each of the chambers *c* comprises a steam receiving compartment *c'* and a steam-discharge compartment

c'', which are divided by an annular partition *e*, the latter being arranged radially (as shown in Figs. 1 and 2) in a plane at right angles to the axis of the turbine. The tubes *b* communicate with compartment *c'* approximately at diametrically opposite points of its periphery and the partition *e* is provided with openings *d* in the intervals between the said tubes, near the middle of such intervals. This arrangement of tubes and 60 openings insures an equal distribution of the steam in the various parts of the chamber, as indicated by the arrows, Figs. 1 and 2, thus securing equal heating and expansion of all parts of the chamber and the retention of its normal shape and position. Compartment *c''* has a central outlet *f* through which the steam flows to the turbine disks. Within the compartment *c'* there is further provided a compartment *c'''* for 65 the overloading steam, said compartment communicating with the intermediate blade rings by means of tubes *g*, said tubes discharging into the annular interval or space before mentioned on the inner face of the 70 wall of said chamber, between the shaft packing and the labyrinth packing *n*. By means of the openings *h* which are closed by valves *i* the compartment *c'''* may be put at 75 will in communication with *c'*, whereby the 80 high pressure steam may be introduced in the lower steps or stages of the procedure, by passing through said central outlet or discharge opening *f* with the steam of ordinary pressure. It will be understood that 85 the desired effect can be substantially obtained even by admitting the steam through two or more tubes *b* which are arranged symmetrically or almost symmetrically. In 90 this case the partition *e* can be omitted.

In the modification illustrated by Fig. 3 the annular partition *e* of each chamber is not arranged radially on edge as in Figs. 1 and 2 but has the form of a cylinder parallel to the axis of the turbine. 95

In the modification shown in Fig. 4 the compartment *c''* is omitted. The tube *b* opens into this modification in a tube *k* placed in the compartment *c'* and provided with holes *l*. By this tube a uniform distribution of the steam in the compartment *c'* is effected. 100

In the modification shown in Fig. 5 the tube *k* is placed outside the chamber *c* and communicates with this latter through the 105

tubes m . Even in this modification there is effected a uniform distribution of the steam in the compartment c' .

Having now described my invention, what I claim and desire to protect by Letters Patent is:—

10. 1. A turbine inlet chamber provided with a partition dividing it into two compartments, one of which connects with a discharge opening, the other with a steam inlet, the said partition being adapted to permit the passage of steam at divers points for distributing it uniformly through said chamber.
15. 2. A turbine inlet chamber adapted to support packing rings and divided by a partition into two compartments, in combination with an inlet tube supplying steam to one of said compartments and the other of said compartments communicating with a discharge opening, the said partition being provided with openings communicating with different parts of the latter compartment for distributing the steam within said chamber.
20. 3. A turbine inlet chamber consisting of two compartments divided by a partition, in combination with two inlet tubes communicating with one of said compartments at approximately opposite points of their circumference and with a partition dividing said compartments from each other, but pro-

vided with openings in the intervals between said pipes for distributing steam in said chamber.

4. A turbine inlet chamber provided with a perforated partition for distributing steam uniformly through said chamber and a supplemental chamber normally discharging independently, but provided with means for opening communication at will between it and the former chamber.

5. A steam chamber adapted to support two sets of packing rings concentrically arranged outside of the same at an interval, said chamber comprising a steam-receiving compartment c' , a discharge compartment c^2 , a radial partition dividing these two compartments, but provided with openings, a third compartment c^3 and an independent outlet therefor normally discharging into the said interval between the said two sets of packing rings, means for distributing the steam uniformly within the former two compartments and means for opening at will communication between compartment c^3 and compartment c' for the purpose set forth.

In testimony whereof I have affixed my signature in presence of two witnesses.

FREDRIK LJUNGSTRÖM.
